(57) **CLAIM**

The ornamental design for a circulation cover for a convection oven, as shown and described.

DESCRIPTION

FIG. 1 is front perspective view of a circulation cover for a convection oven;

FIG. 2 is front view of the circulation cover for a convection oven shown in an environment of use;

FIG. 3 is a front view of the circulation cover for a convection oven;

FIG. 4 is a right-side view thereof;

FIG. 5 is a top view thereof;

FIG. 6 is a rear view thereof; and,

FIG. 7 is a bottom view thereof.

The broken lines in FIG. 2 represent a cooking cavity depicting environment and form no part of the claimed design. All other broken lines in FIGS. 1-7 represent portions of the circulation cover for a convection oven and form no part of the claimed design.

1 Claim, 4 Drawing Sheets
